United States Patent Office

Des. 202,702
Patented Nov. 2, 1965

202,702

PORTRABLE VOLT-OHM-MILLIAMMETER

David S. Wise, 4485 Longleaf Road, Warrensville Heights, Ohio; George E. Sutliff, 8211 Forestdale Drive, Kirtland, Ohio; and Donald B. Coon, 4455 Brookton Road, Warrensville Heights, Ohio

Filed Sept. 14, 1964, Ser. No. 81,718

Term of patent 14 years

(Cl. D26—1)

Fig. 1

Fig. 2

Fig. 3

Fig. 4

Fig. 5

Fig. 6

FIG. 1 is a front perspective view of a portable volt-ohm-milliammeter showing our new design in closed condition;

FIG. 2 is a rear elevational view thereof;

FIG. 3 is a top plan view thereof;

FIG. 4 is a bottom plan view thereof;

FIG. 5 is an end elevational view thereof; and

FIG. 6 is an enlarged perspective view of the portable volt-ohm-milliammeter in open condition.

The essential features of our design are shown in full lines.

We claim:

The ornamental design for a portable volt-ohm-milliammeter, as shown.
